UNITED STATES PATENT OFFICE.

MELVIN C. STONE, OF READING, MASSACHUSETTS.

DESIGN FOR A HAIR-PIN.

47,971.

Specification for Design.

Patented Oct. 12, 1915.

Application filed May 22, 1915. Serial No. 29,915. Term of patent 7 years.

To all whom it may concern:

Be it known that I, MELVIN C. STONE, a citizen of the United States, residing at Reading, in the county of Middlesex and State of Massachusetts, have invented a new, original, and ornamental Design for Hair-Pins, of which the following is a specification, reference being had to the accompanying drawing, forming a part thereof.

The figure is a perspective view of a hair pin, as shown.

I claim:

The ornamental design for a hair pin, showing my new design.

MELVIN C. STONE.

Witnesses:

HENRY A. BALLOU,
G. G. McBRIDE.
